UNITED STATES PATENT OFFICE.

GEO. W. GARDNER, OF TROY, NEW YORK.

IMPROVEMENT IN MOLDING COVERS OF COOK-STOVES.

Specification forming part of Letters Patent No. 23,022, dated February 22, 1859.

To all whom it may concern:

Be it known that I, GEO. W. GARDNER, of the city of Troy, in the county of Rensselaer and State of New York, have invented a new and useful Improvement in Patterns for Molding the Recesses in the Covers of Cook-Stoves; and I do hereby declare the following to be a full and exact description of the same, reference being had to the accompanying drawings, and to the letters and marks thereon.

In casting the covers of cook-stoves in order that the recesses in them should have suitably-formed projections, under which the lifter can be inserted, it has been customary to use small detachable pieces in connection with the main pattern of the cover, these detachable pieces being used to make the necessary depression in the sand, by which would be formed the projections of the recess. In molding with these detachable pieces no degree of carefulness is sufficient to produce perfectly smooth surfaces, for the reason that in taking the patterns from the sand it will be more or less disturbed, and unevenness of surface result.

The object of my invention is to produce by casting a recess with the necessary projections for the lifter, which shall be smooth and of even surface, and thus improve and render more useful this feature or part of the cover; and my invention consists in combining with that part of the pattern which gives form to the recess pivoted projections or lips, whereby form may be given to the projections of the recess for the lifter and the molding of the pattern be conveniently and rapidly performed.

By the drawings forming part of this specification are shown by Figure 1 a top view of a cover, by Fig. 2 a bottom or underside view of a pattern, and by Fig. 3 an upper side or top view of a pattern with one of the pointed projections only.

In Fig. 1, *a* marks the recess, and *b* the pro-

jections for the lifter. In Fig. 2, *a* also marks that part of the pattern which gives form to the recess, and *c c'* mark the pivoted projections or lips for forming the lifter projections, that projection marked *c* being shown turned inwardly in the position in which it makes its impression on the sand, and that marked *c'* being turned outwardly, or in the position in which it does not project upon the sand. In Fig. 3 the recess is also indicated by *a* and the projection *c* only shown.

In carrying my invention into practice the pattern is molded in the usual way with the usual handling of the mold-board and the cope and nowel parts of the flask or box, the pivoted projections *c* and *c'* being turned outwardly from the recess of the pattern, as is represented by *c'*, Fig. 2 of the drawings. The elevation of the sand for forming the recess in the cover is then without any impression of the projections *c* and *c'*. Upon removing the cope of the flask and exposing the pattern it is only necessary to seize the pin *c* of each projection and turn them upon the sand, when the impression will be fully and completely made for forming the projections of the recess of the cover. The pivoted projections of the pattern make upon the sand a very smooth impression, and the cover, when cast, will have a very smooth and perfect recess with firm and durable projections for the lifter.

Having thus set out my invention, what I claim as new, and desire to secure by Letters Patent, is—

Combining with that part of the pattern which gives form to the recess of the cover the pivoted projections, as and for the purposes herein set forth.

G. W. GARDNER.
